UNITED STATES PATENT OFFICE.

ALFRED LORIMER ADRIANSON, OF RACINE, WISCONSIN.

ELEVATOR-BUCKET ATTACHMENT.

1,276,851.

Specification of Letters Patent. Patented Aug. 27, 1918.

Application filed October 12, 1917. Serial No. 196,280.

To all whom it may concern:

Be it known that I, ALFRED L. ADRIANSON, a citizen of the United States, residing at Racine, in the county of Racine and State of Wisconsin, have invented new and useful Improvements in Elevator-Bucket Attachments, of which the following is a specification.

This invention comprehends the provision of a bucket attachment for endless conveyers, and has for its object to prevent stone, gravel and the like which the buckets are conveying, from finding their way between the buckets and the belt, thus prolonging the life of the latter, and reducing the operating expense of the elevator or conveyer to a minimum.

It frequently happens that stone, gravel and the like lodges between the buckets and belt of the elevator, especially as the latter pass over the pulleys, and as the buckets tend to adjust themselves to the belt on the straight away the stone and gravel are forced through the belt creating large jagged holes in the latter. The belt is thus weakened to such an extent, that it must be replaced in order to prevent breaking of the elevator as a whole which would obviously result in considerable damage.

The present invention aims to obviate this trouble, by providing an attachment that is applicable to all types of bucket elevators, and designed to absolutely prohibit the entrance of stone, gravel or the like beneath the buckets, and especially when the buckets discharge their contents into the hopper.

The nature and advantages of the invention will be better understood when the following detail description is read in connection with the accompanying drawings, the invention residing in the construction, combination and arrangement of parts as claimed.

In the drawings forming part of this specification like numerals of reference indicate similar parts in the several views and wherein:

Figure 1 is a side elevation of an elevator showing the attachments associated with the respective buckets.

Fig. 2 is an enlarged plan view of one of

the buckets with the attachment associated therewith.

Fig. 3 is a sectional view taken on line 3-3 of Fig. 2.

Fig. 4 is a plan view of one of the attachments separated from the bucket.

Figure 5 is a sectional view taken on line 5-5 of Fig. 4.

Fig. 6 is an edge elevation of one of the springs.

Referring to the drawings in detail A indicates generally an endless conveyer or elevator which essentially embodies a belt 10 to the outer surface of which is secured a series of buckets 11. Usually, there is a space between the adjacent buckets 11, which is frequently due to stretching of the belt, and when the buckets are utilized in conveying stone, gravel or the like, the contents of the buckets often lodge between the buckets and the belt. This condition has a very ruinous effect upon the belt, as the weight of the bucket and its contents forces the stone and gravel that jams between the buckets and belt, through the latter, and after a number of holes have been thus created in the belt the latter becomes so weakened that it necessitates the replacing of the belt with a new one which requires considerable time and expense.

The present invention embodies an elongated plate 12 which is curved transversely throughout its length and has its opposite longitudinal edges slightly offset as at 13 and 14 respectively. A bar 15 is disposed beneath the plate 12 adjacent the longitudinal edge 14, the bar being riveted to the plate as at 16, or otherwise suitably secured thereto. The plate 12 is cut away at two of its corners as at 17, and the opposite terminals of the bar 15 are exposed in these cut away portions. A pair of leaf springs 18 are employed, each spring having one end arranged within the cut away portion 17 of the plate, and coiled as at 19 to provide a bearing for the adjacent terminal of the rod 15. A washer 20 is fitted upon the bar adjacent each spring, and a cotter pin 21 is subsequently passed through the bar at each end to maintain the springs operatively positioned upon the bar. The springs 18 pro-

ject an appreciable distance beyond the edge 14 of the plate and are provided with openings 22 for the reception of suitable fastening elements for attaching the spring to one of the buckets 11.

As clearly illustrated in Fig. 1 one of the attachments above described is positioned between every two of the buckets 11, the springs 18 being secured to the rear end of one bucket, while the curved plate 12 expands or bridges the space between the respective buckets. The opposite longitudinal edges 13 and 14 of each plate bear against the two respective buckets between which the plate is arranged, with the edge 13 disposed within one of the buckets as shown in Fig. 1. When passing around the elevator there is very little movement of the plate at the edge 14 between the spring, but considerable movement of the plate at the opposite longitudinal edge 13. To provide for this movement the plate extends an appreciable distance within one of the buckets, an arrangement which also allows for the stretching of the belt without a casual derangement of parts. The plate obviously prohibits stone, gravel or the like which is being conveyed in the buckets from gaining access to the space between the latter and the belt, which as above stated has a very detrimental effect upon the belt. The plate 12 adjacent the cut away portions 17 is curved or bent outwardly as at 23 adjacent the coiled terminals of the spring 18, and has a tendency of throwing the stones or gravel away from the sides of the bucket and also from the springs 18. The springs are made with enough play in them to keep the plates tight against the buckets when passing around the pulleys or drums 24, the springs pressing firmly upon the top of one bucket of each pair, on the straightway when carrying the load.

In placing the attachment on used elevator buckets that are worn so badly that wearing strips are necessary, the springs 18 as shown in Fig. 6 are offset at a suitable point in their length as at 25 to permit the wearing plates to be arranged beneath the offset extremity of the spring as will be readily understood.

While it is believed that from the foregoing description the nature and advantages of the invention will be readily apparent, I desire to have it understood that what is herein shown and described is merely illus-

trative of the preferred embodiment of the invention to which I do not limit myself, and that such changes may be resorted to when desired as fall within the scope of what is claimed.

What is claimed is:—

1. The combination with a belt and a series of elevator buckets thereon, of a curved plate bridging the space between each two adjacent buckets, and said plate being hinged at an appropriate point in its width to one of said buckets, with its opposite longitudinal edges bearing against the respective buckets. 70

2. The combination with a belt and a series of elevator buckets thereon, of a curved plate bridging the space between each two adjacent buckets, and resilient means hingedly supporting said plate from one of said buckets with the opposite longitudinal edges of said plate bearing against the respective buckets. 75

3. The combination with a belt and a series of elevator buckets thereon, of a curved plate, a bar secured to one side of the plate, a pair of springs secured to one of said buckets and providing bearings for said bar whereby said plate is hingedly supported on said springs, and said plate bridging the space between each two adjacent buckets with the longitudinal edges bearing against the respective buckets. 80

4. The combination with an endless belt and a series of elevator buckets thereon, each bucket having a closed end and open at its forward end, of a curved plate arranged between each two adjacent buckets, said plate being hingedly supported from one of said buckets, with one of the longitudinal edges bearing against said bucket and the opposite longitudinal edge arranged within the other adjacent bucket and bearing against the bottom thereof, and resilient means exerting a pressure upon said plate. 100

5. The combination with a belt and a series of elevator buckets thereon, of a curved plate arranged between each two adjacent buckets, leaf springs secured to one of said buckets and hingedly supporting said plate, said plate having its opposite longitudinal edges bearing against the respective buckets, and an outwardly curved portion projecting from said plate adjacent each end thereof for the purpose described. 110

In testimony whereof I affix my signature.

ALFRED LORIMER ADRIANSON.
